UNITED STATES PATENT OFFICE.

NELSON A. MILLER, OF NEW YORK, N. Y.

DESIGN FOR A BOX-TRIMMING.

SPECIFICATION forming part of Design No. 26,296, dated November 17, 1896.

Application filed September 22, 1896. Serial No. 606,681. Term of patent 14 years.

To all whom it may concern:

Be it known that I, NELSON A. MILLER, a citizen of the United States, residing in the city, county, and State of New York, have 5 invented a Design for Box-Trimmings, of which the following is a specification.

In the accompanying drawing is shown a rectangular plane surface on which the new design is produced in contrasting shades representing different colors.

The leading feature of the design consists in a box-trimming having a central panel *a* of rectangular form shaded or streaked in contrasting colors. This panel is surrounded by 15 a marginal band *b* of a light color. Outside of this marginal light-colored band is a band *c* of a darker color and of a width greater than the width of the band *b*. Outside this band *c* is another band *d* of a lighter color

than the band *c* and substantially the same 20 color as the band *b*.

The design as a whole represents a rectangular trimming having a relatively larger central panel streaked or shaded as described and shown, surrounded by a frame composed 25 of bands of contrasting colors, the central band being darker and wider than the adjacent inner and outer bands.

What I claim is—

The design for a box-trimming, substantially as shown and described.

In testimony whereof I have signed my name to this specification in the presence of two subscribing witnesses.

NELSON A. MILLER.
